WINDING MACHINE

Louis M. Cotchett, Brookline, Mass., assignor to
Textile Patent & Process Co. Incorporated,
Boston, Mass., a corporation of Massachusetts

Application October 15, 1931. Serial No. 568,891

12 Claims. (Cl. 242—35.5)

The present invention relates to textile apparatus, and more particularly to improvements in machines for winding yarn from a bobbin on to a usable cone package. The present invention is particularly concerned with the prevention and elimination of loose, flying lint which is a normal and usual accompaniment of this type of operation as the yarn is unwound and whipped from the bobbin at winding speeds.

10 I am enabled to eliminate and control this normally loose, flying lint by assembling the wound bobbin or bobbins in a compartment through which is maintained a constant draft of air of sufficient magnitude to remove the lint to any suitable point. In a simple and practical embodiment of the invention I surround each wound bobbin with a cell which is in free communication at the lower portion with a conduit or air trunk through which is maintained a constant draft of air. The wound bobbin is supported upon a skewer in the cell, and the yarn is withdrawn from the upper portion, but due to the constant maintenance of a down draft of air through the cell and about the bobbin, loose or free lint which results from the unwinding of the yarn from the bobbin is withdrawn downwardly into the trunk, from whence it may be removed to a common collecting point. Each cell is so arranged in conjunction with the air trunk that during the winding operation the cell is in communication with the trunk, but is readily shifted therefrom into a bobbin doffing position to permit discharge of the empty or partially emptied bobbin on to a conveyor which removes it from the apparatus.

40 In the accompanying drawings illustrating the preferred form of the invention, Fig. 1 represents a front elevation of a winding machine embodying the features of the invention; Fig. 2 is an elevation partially in section illustrating the frame of the machine with the upper portion removed and showing more particularly the arrangement of the cells and lint-removing ducts; and Figs. 3 and 4 are details illustrating the manually operated mechanism for shifting the cells from winding to doffing position, and vice versa.

45 The machine shown in the illustrated embodiment of the invention comprises generally a frame 10, having a series of rotary guides 12 designed, in cooperation with conical packages 14, to produce a familiar form of crossed wind. The winding mechanism may be conveniently driven in any suitable manner from an electric motor 16. The individual bobbins from which the yarn is withdrawn are indicated at 18 as maintained in

cells 20. Each of these cells, as shown more particularly in Fig. 2, comprises a cylinder open at top and bottom, and normally maintained in the vertical position shown at the right of Fig. 2. In this position the bobbin is supported from beneath by a skewer 24, upon the end of an arm 26, which in turn is connected to the lower end of sliding rods 28, which are adapted to be manually depressed to depress the skewer through an operating handle 30, as will be presently described. When the skewer is depressed the bobbin is left supported upon a stationary ledge 32, and swinging movement of the cell into the inclined doffing position shown at the left of Fig. 2 permits the bobbin to be carried therewith and subsequently discharged upon the surface of a conveyor 34. This conveyor comprises an endless belt running lengthwise of the frame, and having cooperating inclined discharge surfaces 36 and 38, by which the empty or partially emptied bobbins are directed on to the conveyor. The conveyor passes at its opposite ends over pulleys 40 and 42, which may be driven by a chain 44 from a drive shaft 46 operated initially from the motor 16. With this construction bobbins discharged from the individual cells are removed to a common collection point in a manner which will be obvious.

50 During the winding operation the rapid whipping of the yarn from the surface of the bobbin package causes a substantial amount of free flying lint which may collect on the yarn or float freely in the air. I prevent this loose flying lint by placing the lower end of each bobbin compartment in constant communication during the winding operation with a constant draft sufficient to produce a downward suction in the bobbin compartment. To this end I find it convenient to provide an air trunk 50, extending lengthwise of the frame at each side thereof, and communicating with the open lower end of each series of cells when located in winding position. As will be apparent, each air trunk is of generally rectangular cross-section, encloses the bobbin supporting skewer without interfering with the free movement thereof, and is in communication with the lower end of each enclosing cell 20 when the latter are positioned vertically. The two air trunks may each be connected with an exhaust fan producing a suction within the trunk, or may be caused to merge into a single duct connected with a similar fan for removal of loose lint downwardly through the trunks to a common collection point. Obviously, as the lint is free flying and light, a slight draft is ample for the

purpose, and removal of individual cells from winding to doffing position with exposure of the openings in the trunks is not sufficient to seriously affect the necessary draft.

5 As will be evident more particularly from Figs. 3 and 4, the operating handle 30 is supported at the outer end of a shaft 52, which carries an operating arm 54 at its inner end. This arm is designed to engage with a dog 56, supported upon 10 the head 58, and depress the head upon suitable movement of the handle. This depression of the head against the sustaining springs 60 depresses the rods 28 sufficiently to completely remove the supporting skewer from within the bobbin. At 15 the same time a yoke 64, connected to the upper ends of the rods 28, is moved downwardly, and after removal of the skewer the extended ends 66 of the yoke engage with rearwardly projecting arms 68, which pivotally support the cells 20 at 20 70. Engagement of the yoke with the arms depresses the extended ends of the arms and swings the cell outwardly about the pivot 70 into the doffing position shown in Fig. 2.

Connected with the operating arm 54 is a link 25 72, which actuates a rock shaft 74 through an arm 76. This rock shaft supports the thread tension and guide 80 which, by virtue of this movement, is thrown into the rearwardly inclined position shown in Fig. 2 to facilitate delivery of a fresh bobbin to the cell upon repetition of the 30 cycle. When the operating arm 54 has completed its downward traverse, the end of the arm swings by the dog 56, and the head 58 with its accompanying parts are immediately returned by 35 the springs, first moving the skewer to supporting position and returning the cell to vertical position, the cell being provided with a slot 84 in the rear wall to permit entrance of the skewer therethrough. After the fresh bobbin has been 40 assembled within the cell, the actuating arm may be returned to move the thread guide into winding position, this upward movement of the arm 54 being permitted by a pivotal mounting of the dog 56 at 86, as will be evident.

45 What is claimed is:

1. A winding machine comprising means for supporting a yarn package to be unwound, a tubular envelope surrounding the package in process of unwinding, and means for creating a draft of air through the envelope to remove lint released from the package in unwinding.

2. A winding machine comprising means for supporting a yarn package to be unwound, a tubular envelope surrounding the package in process of unwinding, means for leading yarn from one end of the envelope, and means for withdrawing air from the opposite end of the envelope to remove loose lint therethrough.

3. A winding machine comprising means for supporting a yarn package in an upright position, a cell surrounding the package in unwinding position, means for withdrawing yarn through the upper end of the cell, and means for creating a down draft of air through the opposite or lower end of the cell.

4. A winding machine comprising means for supporting a yarn package in an upright position, a cell surrounding the package in unwinding position, means for withdrawing yarn through the upper end of the cell, an air duct communicating with the lower end of the cell, and means

for permitting a draft of air therethrough sufficient to remove lint from within the cell.

5. A winding machine comprising means for supporting a series of upright yarn packages, a series of cells each surrounding a package, an air conduit communicating with the lower ends of the cells, and means for creating a draft of air downwardly through the cells and through the air conduit.

6. A winding machine comprising means for supporting a yarn package, a tubular member enclosing the yarn package, means for moving the tubular member from unwinding to doffing position, an air duct communicating with one end of the tubular member in unwinding position, and means for creating a draft of air through the duct.

7. A winding machine comprising means for supporting a series of yarn packages, a series of tubular members surrounding the yarn packages, means for individually moving the members from unwinding to doffing position, and a common air duct communicating with the ends of the members when in unwinding position.

8. A winding machine comprising a lint-removing duct, a tubular enclosure positioned above the duct communicating therewith, a bobbin-supporting spindle movable within the duct and normally positioned within the movable member when supporting a bobbin, and means under the control of the operator for depressing the spindle and removing the tubular member from an upright unwinding position into an inclined doffing position.

9. A winding machine comprising a tubular cell, means for supporting a bobbin within the cell, means for creating a draft of air through the cell, and means under the control of the operator for removing the bobbin support into inoperative position and thereafter moving the cell from unwinding to doffing position.

10. A winding machine comprising an upright cell, means for supporting a bobbin approximately centrally within the cell and free from contact with the walls, means for leading yarn from the upper end of the cell, and means for creating a down draft of air through the lower end of the cell.

11. A winding machine comprising an upright cell, means for supporting a bobbin approximately centrally within the cell and free from contact with the walls, means for leading yarn from the upper end of the cell, means for creating a down draft of air through the lower end of the cell, and means under the control of the operator for moving the cell from an upright unwinding position to an inclined doffing position to discharge the bobbin therefrom through the lower end.

12. A winding machine comprising an upright cell, means for supporting a bobbin approximately centrally within the cell and free from contact with the walls, means for leading yarn from the upper end of the cell, means for creating a down draft of air through the lower end of the cell, an air duct communicating with the lower end of the cell when in upright position, and means under the control of the operator for moving the cell from an upright unwinding position to an inclined doffing position.
